Patented Feb. 22, 1921.

INVENTOR.

LOUIS BERBERIAN

BY

C. F. Blake

ATTORNEY.

UNITED STATES PATENT OFFICE.

LOUIS BERBERIAN, OF PORTLAND, OREGON.

MOLDER'S SLICK.

1,369,378.

Specification of Letters Patent. Patented Feb. 22, 1921.

Application filed June 17, 1920. Serial No. 339,785.

To all whom it may concern:

Be it known that I, LOUIS BERBERIAN, a citizen of the United States, and a resident of Portland, county of Multnomah, State of Oregon, have invented certain new and useful Improvements in Molders' Slicks, of which the following is a specification.

My invention relates to molders' slicks in general, and particularly to that type of such slicks as are used for working down into dark corners of the mold, and the object of my invention is to provide means upon the slick whereby to shed light upon the work in such corners.

I accomplish the above object by means of the construction illustrated in the accompanying drawing, which is a part of this application for Letters Patent, like characters of reference indicating like parts throughout the several views thereof, and in which:

Figure 1 is a side elevation of a preferred form of my device; Fig. 2 is a perspective view of a similar form except that the foot 25 is slightly modified, and in conformity with usual practice; Fig. 3 is a still further modification of my device shown in perspective; and Fig. 4 is a sectional plan upon line 4—4 of Figs. 1 and 2.

In general my device consists of the ordinary slick for molders' use having a stem 30, a longitudinal blade 6 and a foot 7, and an electric flash light secured to the slick in such a manner as to shed the light upon the foot 7 and the work contiguous thereto.

As a means of thus securing the flash light 8 to said slick I provide upon the latter a clip 9 suitable for grasping the search light and holding the same in place upon the slick 40 in such a manner that the light from the lens 10 of the flash light shines upon the foot 7 of the slick.

In Fig. 1 I show as the preferred form of slick, one having an inclined member 11

upon the rear of the foot 7, the surface of 45 said inclined member being adapted to reflect the light from the searchlight into a path parallel to the foot 7 and thus to light the work in advance of the foot.

In the modification shown in Fig. 3 the 50 foot 7 is attached to a short stem 12 which stem is secured to the body 8 of the flashlight and the blade 6 is secured to a short stem 13 which is secured to the screw cap 14 of the flashlight, thus making the flash 55 light and the slick integral.

My invention may be made of any size, and constructed of any materials deemed convenient and suitable for a device of this character, and while I have illustrated and 60 described a form of construction and arrangement of parts found desirable in materializing my invention, I wish to include in this application for Letters Patent all mechanical equivalents or substitutes that 65 may fairly be considered to come within the scope and purview of my invention as defined in the appended claim.

Having disclosed my invention so that others may be enabled to construct and to 70 use the same, what I claim as new, and desire to secure by Letters Patent is:

A molder's slick; a foot upon said slick substantially at the axis thereof; an inclined member attached to said slick adjacent said foot; and an electric flashlight mounted upon said slick adjacent said inclined member and directing the rays of light thereupon. 75

In witness whereof I claim the foregoing 80 as my own I hereunto affix my signature in the presence of two witnesses at Portland, county of Multnomah, State of Oregon, this 11th day of June, 1920.

LOUIS BERBERIAN.

Witnesses:

C. F. BLAKE,
L. J. ROBINSON.
